UNITED STATES PATENT OFFICE.

ERNEST STUART DANIELS, OF WASHINGTON, DISTRICT OF COLUMBIA.

PACKING CASE OR BOX STRUCTURE.

Application filed February 15, 1923. Serial No. 619,304.

To all whom it may concern:

Be it known that I, ERNEST STUART DANIELS, a subject of the King of Great Britain, residing at Washington, in the District of Columbia, have invented certain new and useful Improvements in Packing Cases or Box Structures; and I do hereby declare the following to be a full, clear, and exact description of the invention, such as will enable others skilled in the art to which it appertains to make and use the same.

This invention relates to shipping cases or crates and more particularly to packing cases for petroleum or general merchandise for which a strong, protective and non-collapsible container may be required to adequately protect the goods from injury incident to careless and rough handling during shipment.

It has heretofore been necessary to bind the ends (or sides) of ordinary shipping boxes with metal strips or stout wire in order to hold the end (or side) pieces or sections together and prevent splintered pieces or portions thereof from falling out of place, allowing the boxes to collapse should the wood crack or split as a consequence of the strain from rough handling.

The object of my invention is to provide an improved box or packing case structure in which the ends (or side) pieces are reinforced in such manner as to positively hold the ends of the boxes together and prevent them from collapsing or breaking apart even though the ends (or sides) may crack or split from top to bottom or from end to end.

Comparative inexpensive of manufacture, simplicity of design, strength and maximum durability in use are further desiderata which have been borne in mind in the production of my improved packing box.

The invention will first be hereinafter more particularly described with reference to the accompanying drawings, which are to be taken as a part of this specification and then pointed out in the claims at the end of the description.

In said drawings, Fig. 1 is a perspective view of an end (or side) section of a packing box, illustrating the application of my invention to the ends or sawed-off portions thereof to reinforce and positively hold the same together.

Fig. 2 is a perspective view of a shallow packing box, one side and the top thereof

being removed to illustrate the application of my improved structure to the vertical ends (or sides) of the box end sections; and

Fig. 3 is a perspective view of a deep packing box, the top being removed to illustrate the improved structure as applied to the horizontal ends (or sides) of the box end sections.

Referring to the drawings, in which like reference numerals are used to denote corresponding parts throughout the several views, 1 denotes a packing box end section which may be made either of a single panel as illustrated in Figs. 2 and 3, or of two or more panels or pieces of planking of the same or different widths and of equal length joined together as illustrated in Fig. 1, depending upon the dimensions desired for the completed box.

The sawed-off or transverse ends of the panels comprising the end sections of the box, are cut or provided with a marginal centrally disposed recess or groove 2 of sufficient depth to permit a wooden strip 3 to be inserted lengthwise therein, where it will be held firmly in place between the marginal bifurcations thus formed by the groove and joined with the section as an inseparable part thereof, the strip 3 lying within the groove with its grain running at cross angles to the grain in the panel or panels comprising the section.

In placing these strips 3 within the grooves provided in the ends (or sides) of the several sections, care should be taken that the grain of the former will run at an angle crosswise to the grain in the latter and preferably at right angles thereto, as the salient feature and value of my improved end section structure in preventing the section from coming apart should the wood crack or split under strain, depends upon such a relation between the two parts. If the strips 3 were inadvertently inserted within the grooves so that the grains ran correspondingly in each they would sympathetically crack or break apart with the panels if split under strain and the very purpose of my improved structure in inserting reinforcing marginal strips within the grooves for retaining the panels in place under such conditions would be lost in consequence.

If desired, the groove 2 and the strip 3 may be coated with a suitable glue to assure a tight union between these parts and

2
prevent the strip from loosening as a result of repeated use or swelling of the wood from exposure to the weather.

Thus it will be readily understood that I have provided a novel improvement in box structure which will be of great commercial value, will effect adequate protection of the goods by holding the box intact and permit an appreciable saving in lumber. The advantages of a packing case or box constructed with my non-collapsible box end-sections will be obvious and the novelty and value residing in my invention may be fully appreciated, since the necessity of employing metal strips or wire to reinforcingly bind and secure the ends of boxes or crates together upon completion will be largely removed.

Having thus described my invention, what I claim as new and desire to secure by Letters Patent of the United States is:

1. A packing case or box constructed with end-pieces of wood, one of said end-pieces having formed in one end thereof a transverse groove extending substantially throughout the width of said end piece, and a strip of wood secured in said groove with the grain of the strip running at an angle crosswise to the grain of said end-piece.

2. A packing case or box constructed mainly of wood and having formed in one of its (sides or) end-pieces a transverse groove extending substantially through the width of said end piece and a strip of wood secured in said groove with the grain of the strip running at an angle crosswise to the grain of said (side or) end.

3. A packing case or box constructed with end panels of wood, said end panels having transverse marginal grooves formed in their respective ends and extending substantially throughout the width of said end pieces, and a reinforcing and strengthening strip of wood secured in each of said grooves with the grain of the strips running at angles crosswise to the grain of said end panels.

4. A wooden packing case or box constructed with wooden end sections, said end sections having marginal grooves formed in their respective transverse ends and extending substantially throughout the width of said end pieces, and uniting strips of wood secured in said grooves with the grain of the strips running at substantially right angles to the grain of said end sections.

5. A packing case or box constructed with wooden end sections comprising a plurality of joined panels of equal length, said section panels having corresponding marginal transverse grooves formed in their respective ends and extending substantially throughout the width of said end pieces, and uniting strips of wood secured in said grooves in opposite sides or ends of said end sections with the grain of the strips running at substantially right angles to the grain of each of the panels in said end sections.

In testimony whereof I affix my signature in the presence of two witnesses.

ERNEST STUART DANIELS.
